UNITED STATES PATENT OFFICE

2,439,726

WINDOW SASH CONSTRUCTION

Stanley Galuska, Chicago, Ill.

Application October 22, 1945, Serial No. 623,674

1 Claim. (Cl. 20—92)

1

The present invention relates to window sash construction and has for its main object the provision of novel means for joining horizontal and vertical sash bars.

A still further object of the present invention is the provision of an interlocking joint between vertical and horizontal sash bars, and which are constructed partially of wood and partially of metal.

A still further object of the present invention is the provision of a suitable joint between vertical and horizontal sash bars, and wherein the sash bars are constructed of wood and lined with metallic plate, and in which joint the wooden part of the sash bars as well as of the metallic lining plates are interconnected.

With the above general objects in view and others that will appear as the invention is better understood, the same consists in the novel construction, combination and arrangement of parts hereinafter more fully described, illustrated in the accompanying drawing and pointed out in the appended claim.

In the drawing forming a part of this application and in which like designating characters refer to corresponding parts throughout the several views:

Fig. 1 is an elevational face view of a window sash;

Fig. 2 is an enlarged cross-sectional view on line 2—2 of Fig. 1; and

Fig. 3 is a cross-sectional view on line 3—3 of Fig. 1.

Referring in detail to the present drawing, there is shown therein a window sash frame generally indicated by 10, and which has a pair of spaced vertical sash bars 11 and a pair of horizontal sash bars 12. Said vertical and horizontal sash bars are suitably interconnected to form joints at the corners of the sash, and which joints are the subject-matter of the present invention.

Each of said sash bars, made of wood, is lined by metallic plate 13. Said metallic plates of each pair of the sash bars 11 and 12, and adjacent one side of the window sash, and inwardly thereof, are doubled upon themselves to effect window pane retaining flange 14. Portions of said flange 14 adjacent each sash bar is beveled at its end as at 15, and the ends of said portions of flange 14 of each adjacent sash bars 11 and 12 are joined by angular metallic plate 16 and rivets 17 or the same, if preferred, may be soldered or welded.

The wooden parts of each vertical sash bar are reduced to effect an integral central tongue 18.

2

The body portions of each of said vertical sash bars 11, adjacent said tongue 18 are undercut to effect tapers 19. The ends of said tongues 18 each has an angular groove 20.

5 The ends of said horizontal sash bars 12 are recessed for defining a pair of spaced rails 21, at each corner of the window sash, within which tongue 18 is receivable, as is clearly seen in Fig. 3.

To retain cover plates 13 of sash bars 11 and 12, within the joint thus formed by tongue 18 and rails 21 within each corner of the window sash 10, said cover plates 13, both in the horizontal and vertical sash bars, are suitably formed whereby said cover plates 13 may enter said joint and be interlocked therein. To accomplish this purpose, cover plate 13 of each of the vertical sash bar 11 and at each end thereof, is angularly bent, as at 22 to conform with and overlie said tapers 19. Thereupon said cover plate 13 of the vertical sash bar 11, on both sides thereof is angularly bent in a vertical direction, for defining a pair of spaced flaps 23 which overlie the two faces of tongue 18 as is clearly seen in Fig. 3.

20 Each rail 21 at each corner of the joint is downwardly beveled in opposite directions to conform to the tapers 19 of the vertical sash bars 11.

25 Cover plate 13 of horizontal sash bars 12 and at each end thereof, is likewise suitably formed to conform to the outlines of rails 21, namely said cover plate 13 at each face of said horizontal sash bars 12, and adjacent the upper and lower beveled edges of said rails 21, is angularly bent to define a pair of substantially parallel lips 24. The pair of inner opposed lips 24 is positioned 30 between the adjacent beveled portions of said rails 21 and the tapered portions of metallic plate 13 of vertical sash bars 11, wherein they are retained, while the outer pair of opposed lips 24 line the beveled faces of the outer edges of said rails 21, and constitute continuation of groove 20 made in tongue 18. The body portion of each horizontal sash bar 12 and between the joints formed therebetween and said vertical sash bars 11 are likewise grooved to provide a 35 continuation of groove defined by groove 20 and outer pair of lips 24, for receiving therewithin angular strips 25, which are maintained in position by a plurality of screws 26 passing through said strips 25 and engaging the wooden body portion of horizontal sash bars 12 between the corner joints hereinabove described. Thus said strips 25 maintain the outer pairs of lips 24 concealed within the joint and in contact with the adjacent beveled faces of rails 21.

40 45 50 55 A plurality of rivets 27 passed through each

corner of window sash 10 and thereby through each tongue 18 and its cooperating pair of rails 21, maintain the wooden portions of the several sash bars as well as the interlocked portions of plate 13 in a rigid position.

From the hereinabove description it will be apparent that the beveled portions 19 of plate 13 at the vertical sash bars 11 and flaps 23 are tucked and embedded between tongue 18 and rails 21. The inner pair of tapering lips 24 contact with and overlie the outer faces of said beveled portions 19, while the outer pair of said tapering lips 24 is engaged by strip 25. By virtue of this construction plates 13 of the horizontal and vertical sash bars at the corners of window sash 10 are maintained in a rigid interlocked position. Tongues 18 and rails 21 are also maintained in a rigid interlocked condition, thereby preventing separation or displacement of the latter due to warping, swelling or other causes.

While there is described herein a preferred embodiment of the present invention, it is nevertheless to be understood that minor changes may be made therein without departing from the spirit and scope of the invention as claimed.

What I claim as new is:

A joint for a pair of fibrous bars, said bars having both sides thereof lined with a metallic plate, comprising a centrally disposed tongue of reduced thickness at an end of one of said bars, there being an angular groove along the free end of the tongue and inclined shoulders at the base thereof which shoulders overlie said tongue, the metallic plate lining the last named bar on both faces thereof also lining said shoulders and both

faces of said tongue, an end of the other of said bars having spaced rails between which said tongue fits, the edges of said rails adjacent the base of the tongue being inclined in parallelism with said shoulders and the edges of said rails adjacent the free end of the tongue being inclined coplanar with the walls of the angular groove along the free end of the tongue to form an enlarged groove, the metallic plate lining the other of said bars on both faces thereof also lining the inclined edges of the spaced rails, an angular strip positioned within and filling said enlarged groove and means rigidly engaging said strip with said tongue and the adjacent inclined edges of said rails for maintaining said rails and lining in a clamped interlocked relation with said first named bar.

STANLEY GALUSKA.
